APPARATUS AND METHOD FOR PRODUCING SOUND

Original application filed October 3, 1930, Serial No. 486,228. Divided and this application filed March 21,
1931. Serial No. 524,342.

This invention relates to methods of and devices for producing sound of a desired or predetermined pitch, tonal quality and intensity.

The inventive method is particularly desirable in connection with the provision of warning signals for use on automobiles, boats or other vehicles.

Heretofore various methods and devices have been proposed for this purpose in which devices and methods as a rule provision has been made for the production of sound waves from a vibrant media or body which is not uniform or consistent and in which it is not possible to uniformly vibrate or move the sound wave generating means in frequency commensurate to or harmonious with the natural periodicity of the media being operated upon, whereby a considerable portion of the sound waves are unintentionally damped, distorted or modified, preventing the acquiring of true sound wave intensity and dispersion.

In devices heretofore provided the tendency has been to provide relatively great intensity of sound without attention being paid to the true form of the sound wave produced, with the result that ragged or distorted waves or tones characterized any device having great intensity or carrying effect as being obnoxious or raucous to the human ear.

We have ascertained that a true and most effective sound wave intensity may be secured by the generation of the waves in media which is substantially uniform and natural and in which the media is acted upon by mechanical means in such fashion that a regenerative resonant effect is obtained, such mechanical means for initiating the sound waves being adjusted to frequency commensurate and in synchronism and rhythm with the vibratory periodicity of the media. The generation of sound waves of true form and maximum intensity will be effected by observance of such principles and produce a warning note or signal which will have greater and more effective intensity or carrying powers and at the same time by reason of the true and clear tone and

form of the note produced, will not be obnoxious to the ear.

In the accompanying drawings, we have illustrated a device embodying a structure illustrative of that which will serve to carry 55 into effect the principles of this invention.

Fig. 1 is a side elevation of a horn embodying one form of our invention;

Fig. 2 is an enlarged longitudinal section through the sound generating end of 60 the horn;

Fig. 3 is a transverse section through the sound generator housing or casing;

Figs. 4 and 5 are diagrammatic illustrations made for the purpose of more clearly 65 setting forth the operation of our horn.

In the device illustrated, a hollow chamber 1 is provided comprising in this particular embodiment, a front section 2 and a back section 3 suitably secured together as by fasteners 3a. The front section may, as shown, be provided with a tubular boss 4 on which is mounted a resonator 5. Within the casing is provided an annular valve seat 6. 8 designates a vibratory valve which constitutes 75 a part of the sound wave generator. As illustrated, a substantial portion of the body of the trumpet adjacent the valve seat is of restricted diameter or bore so as to provide a substantial amount of friction to a column 80 of air in said trumpet and to in effect increase the inertia of any column of air therein.

The valve 8 is resiliently supported with respect to its seat 6, as, for example, by 85 means of the radial springs 11 which are shown as four in number and extended under tension from the inner wall of the sound box to the valve 8. A function of these springs is to normally urge the valve onto 90 or toward its seat. To facilitate and simplify the construction the box section 2 is provided with anchoring portions 13 with which the outer ends of the springs are engaged, and the valve 8 is formed with an axial extension 95 or hub 14 which carries the flange 12 to which the inner ends of the springs are connected. The springs therefore serve to resiliently hold the valve on its seat 6 so as to seal or 100 close communication between the trumpet

passage and the valve chamber 15 within the sound box, this engagement of the valve with its seat being made light or firm by the adjustability of one or more of the parts. Communication is established between the sound box and the intake manifold, or other source of suction, through a conduit 16, which communication is controlled by a readily accessible valve, not shown.

10 The valve 8 may be formed independently of its hub or stem 14 and therefore may embody differing characteristics and materials in its make-up. The spring support for the valve permits bodily movement of the latter 15 unguided otherwise in its movement than by the radial springs. Thus the valve is given a spring suspension permitting the valve to have bodily movement with or without a tension rocking or tilting motion. Therefore, the inertia of the rapidly moving vibrator 8, 14, is given tensioned as well as guided motion through the spring suspension.

15 In the operation of this horn, the chamber 1 is placed in open communication with the intake manifold of the internal combustion engine, as a source of suction, by opening the conduit 16, whereupon a sub-atmospheric pressure will exist within the chamber 1, pulling the valve 8 from its seat 6, or permitting the higher atmospheric pressure within the trumpet 5 to push the valve inwardly from its seat. The atmospheric air entering through the trumpet and being exhausted through the conduit 16 establishes an air stream past the valve 8 and through the valve chamber 1. This unseating of the valve tends to equalize the pressures on both sides of the valve so that the springs will return 20 the valve to its seat, following which the pressure within the chamber 1 will again become rarefied and the valve unseat, and then reseat, whereby a series of condensations and rarefactions are produced in the air, with a resultant throwing of the air stream into vibration.

25 In order to render the radial spring support for the valve more quickly responsive and improve upon the tone of the signal note, as well as increase its pitch, the springs 11 are given an intermediate support, as at 17, the support being conveniently carried by the box section 3. In order to insure the proper tuned relationship between the rate of vibration of the sound wave generator and the air column within the trumpet 5, the support 17' is made adjustable by a stud 18 which is threaded through a boss 19 and the adjustment secured by a jam nut 20.

30 In the production of sound with this device, the chamber 1 is placed in communication with the source of reduced pressure, as for example, by being connected through the conduit 16 to the intake manifold of an internal combustion engine. By reason of such connection, upon operation of the engine a

sub-atmospheric condition of pressure will be created in the chamber 1 and the front end or bell of the trumpet being open to the atmosphere, the column of atmospheric air in the trumpet will push the valve 8 from its seat against the action of the springs 11. Starting its movement, as the valve does, with atmospheric pressure on one face and a minimum sub-atmospheric pressure condition on the other face, as the mass of the valve and its supporting springs is set in motion, the movement coupled with the inertia of these parts is translated to momentum which carries the valve farther back past its normal point of equilibrium.

35 The unseating of the valve permits atmospheric air to enter the chamber 1 and as the pressure of the atmospheric air in the body of the trumpet and the pressure in chamber 1 approach equalization, although full equalization is probably never attained or even approximately attained, the springs which have been stressed beyond the point necessary to support the valve against the differences in pressure in the device, owing to the momentum of the valve, as referred to above, force the valve forward and onto its seat, following which, in like manner, the atmosphere in the chamber 1 will again become rarefied and the valve unseat and then 40 reseat in rapid vibration. As the valve is seating or reseating the conditions in the trumpet are that a column of atmospheric air is present therein flowing toward and past the valve and that the confining effect of the walls of the restricted portion of the trumpet increase or add to the normal inertia of such column of air. As the valve reseats, it appears that there is in the restricted portion of the trumpet some compression 45 of the atmospheric air therein with the effect that the sound waves, the initial generation of which are completed upon the reseating of the valve, are projected into an atmosphere which is substantially uniform or consistent and at the same time supply greater than atmospheric pressure which, of course, accelerates the movement of the sound waves through the vibratory medium confined in the trumpet. At the moment of initial generation of the sound waves it will thus be observed that there is a complete severance or cutting off of the vacuum or reduced pressure influence from the air under atmospheric pressure, and that the sound waves 50 are generated and transmitted to the conducting material in a uniform media.

55 This results in the discharge of sound waves to the atmosphere of true tone and consistency, resulting in the securing of true tonal effects on the ear of the auditor and in the maximum intensity or effective carrying power of such sound waves.

60 As the valve 8 moves toward its seat, it positively interrupts all of the column of air

which was heretofore flowing past the valve, as the force which moves the valve is the pressure of the atmospheric air in the horn when the space in the rear of the valve is partially evacuated and as the restricted walls of the horn confine the air column somewhat adjacent to the valve, that column of atmospheric air regulates or governs the celerity with which the valve returns towards its seat. Therefore, it is found that the vibration of the valve being under control or modified by the column of air in the horn, the period of vibration of the valve is regulated or modified to substantially the period of vibration of the air column in the horn.

The resonator 5 defines a relatively long and narrow air column preferably having a very slight taper so that the air column will be of substantial length without any considerable increase in the diameter. The resonator will therefore not reflect sound waves back and forth across the main longitudinal sound waves in disturbance of the latter, and the resultant tone will therefore be clear and mellow.

It is to be observed that the sound wave is produced with slight pressure differential. The fluid pressure in the resonator is normally atmospheric while that in the conduit 16 is normally slightly below atmospheric, and therefore the sound generation is effected in a medium which is just about natural as distinguished from pressure types of horns having an operating pressure which is greatly in excess to the atmosphere, the increased differential in the pressure type horn effecting a forced or strained vibration regardless of the air column in the trumpet. Such a forced vibration of the sound generator is obviously unnatural and is therefore productive of unnatural noises and sounds which are raucous and unpleasing to the ear.

We have found that under the slight differential under which we operate our horn that the valve or sound generator is given a wide amplitude in its movement and this we account for in the following manner:

The valve is given a definite body or mass and is given a resilient mounting the resiliency of which is adjusted to the air column in the resonator. Then upon providing a pressure differential which is sufficient to initially unseat the valve, a vibration of the latter is set up against the inward movement of the air column from the resonator into the chamber 1 and out through the conduit 16. The sound waves in the air column within the resonator move forwardly and produce reflected sound waves, resulting in surges or pulsations which are substantially in rhythm and synchronism with the vibration of the valve. This results in a regenerative action on the valve 8 so as to increase its amplitude over and above that initially imparted to it by the pressure differential alone.

It is believed that this regenerative effect will be more clearly understood by referring to Figs. 4 and 5 which depict our theory of this sound regeneration. In these figures the resonator 5 is diagrammatically illustrated along with the sound generator or valve 8. Assuming that the valve has been withdrawn from its seat by the initial pressure differential and the air column in the resonator is moving inwardly past the valve, with the latter starting toward its seat as indicated by the arrow in Fig. 5, there will be a slight rarefaction at the inner end of the resonator. But as the valve mass moves quickly to its seat against the inward movement of the air column it will tend to slightly compress the air at the seat, so that when the latter is fully seated there is a pressure built up in the inner end of the resonator acting increasingly greater upon the valve to unseat the same. The trumpet of the resonator having a length substantially equal to one half of the length of the sound wave, there will be a crest or condensation at the inner end of the air column as the valve seats with a rarefaction or valley at the outer end of the resonator, and as the crest moves outwardly to the outer end of the air column there will be a rarefaction at the inner end and that these pulsations will surge and reflect back and forth within the resonator substantially in synchronism with the movement of the valve. Therefore after the valve has seated and built up a pressure at the inner end of the air column the reflected sound wave or surge moving inwardly strikes against the valve substantially at the moment the valve is ready again to leave its seat so that the inwardly moving surge gives to the valve an added impetus.

This occurs for each movement of the valve and builds up a greater amplitude of movement so that as the valve unseats it will draw in a larger volume of atmosphere, increasing the inward movement of the air column and having a faster moving column of air to seat against as the valve returns to its seat. Thus the valve action is built up in a regenerative manner to such an extent that in tests made it has been found that the moving valve body will rebound against the spring support 17, an extent of movement which is not attained in the absence of the resonator. In addition to this regenerative movement in the valve there is also a regenerative production of sound whereby the volume of the sound waves is increased to carry long distances, the sound waves being produced under the natural period of vibration of the valve, in the presence of a small pressure differential.

As an example of this tuned frequency or relationship between the sound generator and the resonator, we provide a resonator having an approximate length of $19\frac{1}{4}$ " with an inside diameter at its smaller end of approximately $\frac{3}{8}$ " flaring to a diameter at its larger

end, where it merges into the bell, of approximately $1\frac{1}{4}$ ". The valve seat has an inner diameter of $\frac{13}{16}$ " on which seats the valve disc having a diameter of $\frac{33}{32}$ ". The valve disc and its body or mass has a weight of $6\frac{3}{10}$ grams and is suspended from four corner posts, diagonally spaced apart $2\frac{3}{8}$ ", by four coiled springs normally about $\frac{5}{8}$ " in length in addition to their attaching terminals or loops. The normal outside diameter of the spring coil is $\frac{5}{2}$ ", and when the springs are stretched from their posts 13 to suspend the valve, as shown in the drawings, there is an approximate pull of three pounds and three ounces.

The pressure or spring support 17 engages the springs adjacent their intermediate portions and is adjusted to give the proper resiliency in the mounting of the valve by turning the screw 18 inwardly.

The foregoing dimensions, weights and other factors are given in approximate figures for producing a tuned valve vibration in synchronism with the air column in the resonator whereby the surges or pulses in the air column produce a regenerative action not only on the valve but also on the sound waves.

The sound generator per se constitutes the subject-matter of our co-pending application filed October 3, 1930, under Serial No. 486,228, the present application being a division thereof.

What is claimed is:

1. An audible signal for automotive vehicles comprising a cone-shaped horn opening through a valve seat, a valve suspended at the apex of said horn to vibrate on the seat, said horn being of size and shape to utilize the surge of an air column to effect a tuned, timed, synchronous movement of the valve in the direction of the surging air, and means for starting and aiding the surging of the air by moving the said valve by atmospheric pressure when the said valve is placed in communication with the intake manifold of an internal combustion engine.

2. In a fluid operated sound producing device, the combination of a resiliently mounted valve suitably loaded so as to have a natural movement of a fairly definite periodicity, with a trumpet of suitable length and proportion so that the natural periodicity of the sound wave in its air column will correspond substantially with that of the valve or valve assembly, said trumpet being tapered and arranged with its smaller end in communication with said valve through a cooperating valve seat, so that the synchronized impinging of air impulses upon the valve will thereby have a regenerative effect upon the valve thereby to increase the amplitude of its movement, in order that this increased amplitude will in turn cause a further regenerative increase in the intensity of the sound wave movement in the trumpet and thereby pro-

duce a further increase in the volume of the sound emitted from the trumpet.

3. A method of producing a signal note or tone consisting in providing a resonator having a definite air column confined at one end by a cylindrical body and opening therefrom through an annular valve seat, resiliently supporting a sound generating valve of a definite inertia on the seat, adjusting the tension of the spring support whereby the rate of vibration of the valve to and from the seat will be in synchronism with the reflected pulsations in the air column to increase the amplitude of the valve and produce a regenerative action, and then providing a pressure differential on opposite sides of the valve to vibrate the latter.

4. In a fluid operated sound producing device for motor vehicles, the combination of a resiliently supported valve suitably loaded or of a suitable mass so as to have a movement of a substantially definite periodicity, with a trumpet of suitable length and proportion so that the natural periodicity of the sound waves in its air column will correspond substantially with that of the valve, said trumpet being arranged with its smaller end in communication with said valve.

5. In a fluid operated sound producing device for motor vehicles, the combination of a resiliently mounted valve of a mass to have a fairly definite periodicity to its natural movement, with a tapered trumpet of a length and proportion that the natural periodicity of the sound waves in its air column will correspond substantially with that of the valve, said trumpet being arranged with its smaller end in communication with said valve through a cooperating valve seat.

6. The method of manufacturing tuned signalling horns, consisting in connecting a resonator, which has a definite air column opening at its smaller end through a valve seat, to a valve of a definite body inertia and which is resiliently supported for vibratory movement to and from said seat for interrupting the movement of the air column in the resonator, establishing an air flow from the resonator through the valve seat to move the valve away from its seat in a manner to set it in sound generating vibration, and then varying the resiliency in the support of the valve to synchronize the vibration of the latter with the pulses in the air column of the resonator for the regeneration of sound waves.

7. A method of producing sound of predetermined characteristics consisting in inducing a column of atmospheric air to move through a column confining device, and in periodically and forcibly interrupting and releasing said movement in timed frequency commensurate with the vibratory period of said column so confined.

8. In a sound producing device, means for

- releasably confining a sound wave transmitting and character changing medium of a predetermined period of vibration, a restricted passage portion in said device, a valve 5 adapted to seat on and close the restricted portion of said device, means for causing said medium to move into the device and past said valve, said valve being adapted and arranged to periodically close said valve against 10 the flow of said medium to interrupt and stop the passage of said medium at a frequency commensurate with the vibratory period of said medium, whereby said medium is rendered fully vibrant.
- 15 9. A horn comprising a support having a passage therethrough and an annular seat about the passage at one side of the support, vibratory valve means resiliently yieldable to and from said seat and operable with a 20 predetermined rate of vibration for the production of sound, a resonator defining an air column acting to reinforce the sound waves therein, said resonator opening at one end to the atmosphere and having its opposite 25 end communicatingly connected to the passage of the support at the side thereof opposite from the seat, and means for creating a flow of fluid from the resonator through the passage and past the valve means.
- 30 10. A horn comprising a resonator confining a definite air column, a casing having a chamber into which one end of the resonator opens, an annular seat within the chamber through which communication is had 35 with the resonator, a valving member coacting with the seat to interrupt intermittently the movement of the air column from the resonator into the chamber through the seat, and a resilient support for the valving member 40 adjusted to return the latter to its seat in rhythm with the sound wave surges in the air column of the resonator to create a regenerative action on the valving member for enhancing its movement.
- 45 11. An audible signal comprising a trumpet confining an air column at substantially atmospheric pressure and having a definite natural periodicity for sound waves, said trumpet flared and opened to the atmosphere 50 at one end and opening at its opposite end through a seat, and a member vibratory on the seat in the presence of such atmospheric pressure at a frequency of vibration in synchronism with the natural periodicity of 55 the sound waves in the air column whereby the synchronized air impulses in the air column will impinge upon the vibratory member in a regenerative capacity to increase the amplitude of movement of said vibratory 60 member in the presence of such atmospheric pressure, and means for setting said member in vibration.
